CLOCK

John L. Hancock, Chicago, Ill., assignor to Mastercrafters Clock & Radio Co., Chicago, Ill., a corporation of Illinois

Application July 8, 1953, Serial No. 25,843

Term of patent 3½ years

(Cl. D42—7)

To all whom it may concern:

Be it known that I, John L. Hancock, a citizen of the United States and a resident of Chicago, in the county of Cook and State of Illinois, have invented a new, original, and ornamental Design for a Clock, of which the following is a specification, reference being had to the accompanying drawing, forming a part thereof, and in which:

Fig. 1 is a front perspective view of a clock showing my design; and

Fig. 2 is a side elevational view thereof.

The back is conventional.

I claim:

The ornamental design for a clock, as shown and described.

JOHN L. HANCOCK.
